TAPE FEEDER FOR PACKAGING MACHINES

John D. Merrifield, Rocky Ford, Colo., and Edgar E. Merrifield, Minneapolis, Minn.

Application January 9, 1948, Serial No. 3,584

1 Claim. (Cl. 242—75)

1 This invention relates to a device for feeding strips of tape into a sewing machine so that they may be stitched upon opposite sides of the neck of a bag for sealing the latter. Many devices have been devised for feeding tape to bag stitching machines for this purpose. All of them have been more or less unsatisfactory due to the fact that the tapes used for this purpose are usually formed from paper, are very fragile and constantly subject to breakage, due to starting and stopping of the machine.

Tape breakage usually results from the fact that the reels of tape rotate relatively rapidly, and when the machine stops their momentum causes them to continue to rotate for a short period, producing a slackness in the tape. When the machine is again started, this slack is suddenly taken up and the resulting jerk in overcoming the inertia of the stationary reel results in breaking the tape.

The principal object of this invention is to provide a tape feeding device for bag stitching machines which will eliminate the constant breakage of the tapes.

Another object of this invention is to provide a device in which the tape reel will be mechanically rotated so that there will be no strain upon the tape, and to provide automatic braking means for quickly stopping the tape reel should the machine come to rest so as to avoid slackness in the tape.

Other objects and advantages reside in the detail construction of the invention, which is designed for simplicity, economy, and efficiency. These will become more apparent from the following description.

In the following detailed description of the invention, reference is had to the accompanying drawing which forms a part hereof. Like numerals refer to like parts in all views of the drawing and throughout the description.

In the drawing:

Fig. 1 is a front view of the improved tape feeding device, illustrating it in combination with a bag stitching machine; and

Fig. 2 is a side view thereof.

In the drawing, a typical bag is illustrated at 10, to the opposite sides of the neck of which two tapes 11 and 12 are to be stitched by means of a conventional sewing machine 13. This invention relates to means for feeding the two tapes 11 and 12 to the opposite sides of the neck of the bag 10 so that they may be stitched thereto.

2 The tape 11 is unreeled from a tape reel 14, and the tape 12 is unreeled from a similar tape reel 15. The reels 14 and 15 are freely rotatable upon a stationary reel shaft 16 which is supported from, and projects oppositely outward from, a vertical standard 17. The standard 17 is secured to and extends upwardly from a base plate 32 supported upon angle brackets 33 from an upright frame 34.

10 A plate 18 is mounted on top of the standard 17. Two tilting brackets 19 are mounted on opposite sides of a pivot post 20 projecting upwardly from the plate 18. The brackets 19 extend rearwardly to receive pull-down springs 21 and extend forwardly to receive resilient pulley rods 22, each of which supports a tape pulley 23.

The tape 11 is led from the reel 14 over one of the pulleys 23, thence downwardly into a flattened tape guide tube 24 supported on the sewing machine 13. The guide tube 24 guides the tape 11 downwardly, thence inwardly into the path of the needle of the sewing machine 13 along one side of the neck of the bag 10.

The tape 12 is led from the reel 15 over the 25 other pulley 23, thence downwardly about a guide pulley 25, thence horizontally into a second tape guide tube 26, which is curved to guide the tape 12 into the path of the needle of the sewing machine 13 onto the opposite side of the bag 10.

30 It can be readily seen that the advancing action of the sewing machine will advance the bag 10 and the two tapes 11 and 12 through the machine causing the tapes to rotate the reels 14 and 15. The tapes are unreeled from their respective reels by positively rotating the reels 14 and 15. This is accomplished from any suitable driving motor (not shown) through the medium of an endless drive belt 27. The drive belt rotates a drive pulley 28 mounted on a countershaft 29 which is rotatably mounted in bearings 30 mounted upon bearing posts 31 extending upward from the plate 32.

Two pulleys are secured to the inner face of 45 each of the reels 14 and 15, there being an inner brake pulley 35 and an outer driven pulley 36. The pulleys 35 and 36 are secured together in pairs and each pair is secured to its respective reel so as to rotate therewith about the axis of the shaft 16.

50 The countershaft 29 carries two pulleys 37, each of which is connected with one of the pulleys 36 by means of an endless belt 38. An idler pulley 39 is held against the tension side of each belt 38. The idler pulleys are mounted on arms 55 40 which are pivotally mounted upon a hinge

shaft 41 extending oppositely outward from the standard 17. Each arm 40 is constantly urged upwardly by means of a tension spring 42. Thus, it can be seen that rotation of the pulley 28 in a counter-clockwise direction in Fig. 2 will cause the reels 14 and 15 to unreel their tapes.

A flexible brake member 43 extends downwardly from the plate 18 ahead of each brake pulley 35, thence returns around each pulley and upwardly to one of the tilting brackets 19. Thus, the action of the springs 21 in pulling the brackets 19 upwardly also acts to tighten the brake members 43 about their respective brake pulleys 35 to exert a braking action on the drums 14 and 15.

The sewing machine 13 is mounted on a vertical plate 44 supported on the frame 34. The sewing machine is driven in any conventional manner (not shown). The thread, indicated at 45, for stitching the two tapes to the bags is carried on a thread spool 46.

When the sewing machine 13 is operating, the reels 14 and 15 are being rotated forwardly at their tops, by means of the belts 38, to unreel the tape and the pulleys 23 are drawn downwardly by the tension in the tapes. Should either tape unreel faster than it can be used by the sewing machine 13, or should the sewing machine be stopped for any reason, a slackness will be created in the tape or tapes. This allows the tape pulleys 23 to move upwardly under the influence of the springs 21 and causes the bracket arms 19 to apply tension to the brake means 43. This retards rotation of the reels, causing the tension side of the belts 38 to force the idler pulleys 39 outwardly. This slackens the belts and allows them to slide over the pulleys 36, with the reels 14 and 15 either moving at a slower speed or remaining stationary until the slackness in the tapes has been taken up.

Tapes are often broken in the usual apparatus by the sudden starting of the machine. In this device a sudden start will first flex the pulley rods 22, then flex the springs 21 so as to absorb the starting shock in the tape. By this arrangement both tapes 11 and 12 are maintained under a constant mild tension, regardless of irregular operating conditions and regardless of the quantity of tape on the reels 14 and 15.

While a specific form of the improvement has been described and illustrated herein, it is desired to be understood that the same may be

varied, within the scope of the appended claims, without departing from the spirit of the invention.

Having thus described the invention, what is claimed and desired secured by Letters Patent is:

A device for feeding tape to a sewing machine of the type used for stitching the neck of a bag for sealing the latter, comprising: two tubular tape-guiding members terminating at said sewing machine; two tape reels mounted above said machine; a hingedly mounted pulley rod extending forwardly from each tape reel; a pulley supported by each rod; a tape extending from each tape reel over one of said pulleys, thence downwardly to one of said tape-guiding tubes; a spring urging each pulley rod upwardly to support said tape between its reel and the machine; a brake drum on each reel; a flexible brake band extending from a fixed support about each brake drum, thence upwardly to one of said pulley arms so that when said pulley arm is pulled downwardly by its tape, said brake band will be released; a counter-shaft mounted parallel to said reels; drive pulleys on said reels and on said counter-shaft; a drive belt extending from each reel to one of the pulleys on said counter-shaft; an idler pulley bearing against the tension side of each belt; a hinged idler arm supporting each idler pulley; a spring acting against each idler arm to hold said idler pulley against the tension side of each belt; and means for driving said counter-shaft.
